(57) **CLAIM**

The ornamental design for an area luminaire, as shown and described.

DESCRIPTION

FIG. 1 is a top perspective view of a first embodiment of the design;

FIG. 2 is another top perspective view thereof;

FIG. 3 is a bottom perspective view thereof;

FIG. 4 left side elevational view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a bottom perspective view of a second embodiment of the design;

FIG. 10 is a bottom plan view thereof, with the remaining views identical to those of FIGS. 1, 2, 4, 5, 7, and 8;

FIG. 11 is a bottom perspective view of a third embodiment of the design; and,

FIG. 12 is a bottom plan view thereof, with the remaining views identical to those of FIGS. 1, 2, 4, 5, 7, and 8.

The broken lines are for illustrative purposes only and form no part of the claimed design.
